(57) CLAIM

I claim the ornamental design for a pool cleaner, as shown and described.

DESCRIPTION

FIG. 1 is a perspective view of a pool cleaner;
FIG. 2 is a front view of a pool cleaner;
FIG. 3 is a rear view of a pool cleaner;
FIG. 4 is a left-side view of a pool cleaner;
FIG. 5 is a right-side view of a pool cleaner;
FIG. 6 is a top plan view of a pool cleaner; and,
FIG. 7 is a bottom plan view of a pool cleaner.
The details shown in broken lines form no part of the claimed design.
